UNITED STATES PATENT OFFICE.

MICHAEL JOSEPH GRANEY, OF PITTSBURGH, PENNSYLVANIA.

FURNACE.

1,387,537.

Specification of Letters Patent. Patented Aug. 16, 1921.

Application filed October 7, 1920. Serial No. 415,433.

To all whom it may concern:

Be it known that I, MICHAEL JOSEPH GRANEY, a citizen of the United States, and a resident of Pittsburgh, in the county of 5 Allegheny and State of Pennsylvania, have invented certain new and useful Improvements in Furnaces, of which the following is a specification.

My invention relates generally to furnaces and more particularly, although not necessarily, to hot air furnaces for burning natural or coal gases, the purpose of my invention being the provision of a simple, durable and inexpensive furnace having a hot 10 air chamber and gas passages so associated therewith as to transmit to the chamber with the greatest degree of efficiency all the heat generated by the burning gases without the latter coming in actual contact with the air 15 to be heated. Furthermore my invention provides a fresh air chamber which communicates with the gas passages in a manner to cause the combining and intermixing of the air and gases to further combustion 20 of the gases.

I will describe one form of furnace embodying my invention and will then point out the novel features thereof in claims.

In the accompanying drawings:

30 Figure 1 is a view showing in longitudinal section one form of furnace embodying my invention.

Fig. 2 is a vertical transverse section taken on the line 2—2 of Fig. 1 and looking in the 35 direction of the arrows.

Referring specifically to the drawings, in which similar reference characters refer to similar parts, F designates a fire box above which is arranged a hot air chamber C, and 40 in the rear of which is formed an air chamber C'. The fire box F contains a grate G of conventional form upon which is supported coal or other gaseous fuel which is introduced into the fire box through an opening 45 formed in the front wall thereof. Air is admitted to the fire box F at a point below the grate G through a port 16 formed in the front wall of the fire box. The draft created by this admission of air 50 causes the gases from the burning fuel to pass upwardly and over the upper end of a bridge wall B, the latter being arranged in spaced relation to the rear wall 17 of the fire box so as to provide between the two a vertical passage 18. The lower end of the rear wall 17 is recessed to provide a port

19 which effects communication between the passage 18 and a vertical passage 20 that is formed between the rear wall 17 and the front wall 21 of a fresh air chamber C'. 60

Fresh air from a point exteriorly of the building in which the furnace is arranged is supplied to the hot air chamber C through a pipe P which communicates with the rear end of an air heating chamber C², the forward end of the latter in turn communicating with the air chamber C at a point substantially intermediate its ends. As illustrated to advantage in Fig. 2, the chamber C² is of rectangular form in cross section, 70 with one portion thereof of a greater cross sectional area than the other portion so as to provide a shoulder 22 interiorly of the chamber and against which the incoming air is adapted to impinge. The side walls 75 of the chamber C² are spaced from the side walls of the furnace to provide vertically extending passages 23 which are coextensive in length with the chamber and communicate at their lower ends with a horizontal 80 passage 24 through the medium of ports 25 arranged at the rear end of the horizontal passage 24. The horizontal passage 24 is formed by a spacing apart of the lower wall of the chamber C² to the upper wall of the 85 chamber C', the front wall 21 projecting above the upper wall of the chamber C' so as to direct the burning gases against the shoulder 22 and downwardly into the passage 24. The vertical passages 23 communicate with a horizontal passage 26 at their forward ends through the medium of ports 27 as illustrated to advantage in Fig. 2, the opposite end of the passage 26 communicating with a vertical passage 28 which 90 latter in turn communicates with chimney or discharge flue 29.

Air is admitted into the air chamber C' by a port 31 formed at the bottom of the rear wall of the chamber, such air being directed upwardly through the chamber and ultimately into the vertical passage 20 by means of a partition T which is arranged in spaced relation to the front wall of the chamber C' to provide a vertical passage 32 95 through which the air passes downwardly from the chamber and into the lower end of the passage 20 through a port 23.

In the operation of the furnace, the burning gases leaving the fire box F pass downwardly through the passage 18 entering the lower end of the passage 20 through the port

19. As the gases enter the passage 20 air through the chamber C' is intermixed with the gases for the purpose of increasing the combustion of the gases and thereby securing a greater heat efficiency. It will be understood that because of the direction of flow of the burning gases from the fire box, a draft is created inwardly of the air chamber C' so that a constant supply of air to the burning gases is at all times maintained. From the passage 20, the gases impinge upon the outer side of the shoulder 22 and are there directed downwardly and into the horizontal passage 24. The gases thus traverse the entire length of the passage 24 where they enter the vertical passages 23 through the ports 25, passing upwardly through the passages 23 and into the horizontal passage 26 through the ports 27. It is to be particularly noted that during the passage of the gases through the passages 24, 23 and 26 that both side walls and the top wall of the chamber C² are traversed by these hot gases so that a most thorough heating of the chamber is effected. Thus, as the fresh air traverses the chamber C² in passing into the chamber C, an intense heating of the air is obtained. After the heated air enters the chamber C, a further heating of the same is effected because one portion of its bottom wall is exposed to the fire box F, while another portion absorbs the heat from the burning gases as they traverse the passage 26. The heated air passes from the chamber C to the desired points of a building through the several pipes P' while the burnt gases from the passage 26 enter the vertical passage 28 and leave the furnace through the flue 29.

40 In the construction of the furnace all of its walls and partitions forming the chambers and passages are constructed of a heat absorbing material such as fire brick so that the heat from the burning gases can readily pass into the air heating chambers, thus causing the heating properties of the gases to be completely spent between the passage of the gases from the fire box to the discharge flue.

50 Although I have herein shown and described only one form of furnace embodying my invention, it is to be understood that various changes and modifications may be made herein without departing from the spirit of the invention and the spirit and scope of the appended claims.

I claim:

1. A furnace comprising, a fire box, a hot air chamber above the fire box and con-

tiguous thereto, an air heating chamber communicating with the hot air chamber, and passages formed in the furnace to direct the burning gases against the bottom wall of the hot air chamber and completely around the air heating chamber.

2. A furnace comprising, a fire box, a hot air chamber above the fire box and contiguous thereto, an air heating chamber communicating with the hot air chamber, and passages formed in the furnace to direct the burning gases against the bottom wall of the hot air chamber and completely around the air heating chamber, the walls of said chambers, passages and fire box being constructed of fire brick.

3. A furnace comprising, a fire box, a hot air chamber above and contiguous to the fire box, an air heating chamber communicating with the hot air chamber, passages for directing the burning gases from the fire box into contact with the lower wall of the hot air chamber and beneath, around, and above the air heating chamber, and means for admitting fresh air into said passages.

4. A furnace comprising, a fire box, a hot air chamber above and contiguous to the fire box, an air heating chamber communicating with the hot air chamber, passages for directing the burning gases from the fire box into contact with the lower wall of the hot air chamber and beneath, around and above the air heating chamber, and a fresh air chamber communicating with said passages in a manner to effect the introduction of air into the passages.

5. A furnace comprising, a fire box, a hot air chamber above and contiguous to the fire box, an air heating chamber communicating with the hot air chamber, passages arranged to direct the burning gases from the fire box longitudinally beneath the air heating chamber, upwardly and longitudinally of the sides of the chamber, and longitudinally over the chamber.

6. A furnace comprising, a fire box, a hot air chamber above and contiguous to the fire box, an air heating chamber communicating with the hot air chamber, passages arranged to direct the burning gases from the fire box longitudinally beneath the air heating chamber, upwardly and longitudinally of the sides of the chamber, and longitudinally over the chamber, and shoulders formed in said air heating chamber and in one of said passages for the purpose described.

MICHAEL JOSEPH GRANEY.
